UNITED STATES PATENT OFFICE.

JOHN B. MOFFATT, OF MONTOUR, IOWA.

IMPROVEMENT IN FEED-STEAMERS.

Specification forming part of Letters Patent No. 179,862, dated July 18, 1876; application filed
March 17, 1876.

To all whom it may concern:
Be it known that I, JOHN B. MOFFATT, of Montour, in the county of Tama and State of Iowa, have invented an Improved Feed-Steaming Apparatus, of which the following is a specification:

The object of my invention is to improve the construction and operation of a feed-steaming apparatus. It consists in the manner of forming and adapting a portable metal furnace and a wooden boiler having metal ends, to be combined and operated as herein-after fully set forth.

My drawing is a sectional elevation, illustrating the construction and operation of my apparatus.

A represents the boiler. B is the furnace. a is the top plate of the boiler. a" is the bottom plate. They are made of wood—preferably of two-inch plank—and joined to corresponding side plates in any suitable manner. They may vary in dimensions to form a boiler of any size desired. b b are cast-metal end plates, to which the wooden top and bottom and side plates are fitted. They correspond in size with the open ends of the wooden boiler, and have flanges to aid in producing steam-tight joints. c c are rods passed through the end pieces, to draw and clamp and retain the metal plates b on the ends of the wooden boiler. d d represent hoops surrounding and binding the boiler. No. 1 represents a series of metal tubes, all in the same plane, passing longitudinally through the lower portion of the boiler. g is a chamber formed on the inside of the rear end plate b, to which the two series of tubes are connected. h is a movable cover on the outside of the chamber g. J represents a boiler-feeder. m is an education-port, to which a flexible tube, n, is attached, to convey steam to the vessel containing the food to be steamed. p is an escape-valve. r is the combustion-chamber of the furnace. It has openings leading into and connecting with the series of No. 1 tubes in the boiler. s is an auxiliary chamber on top of the chamber r. It has openings to connect with the No. 2 series of tubes in the boiler. t is the smoke-pipe, connected with

the smoke-chamber s. x is a hinged cover or door, through which fuel is passed into the combustion-chamber.

The boiler A may rest on the ground, and the furnace B be set in a pit; or the furnace may rest on the ground, and the boiler on feet, as indicated by broken lines.

The furnace is attached to the front end of the boiler by means of suitable catches, or in any way desired, so that they can be readily connected and disconnected, for convenience in moving about the apparatus.

In the practical operation of my invention water is put in the boiler and fire started in the furnace. The products of combustion will pass from the fire-chamber r into and through the series of No. 1 tubes, to the chamber g at the rear end of the boiler, and from thence forward again through the No. 2 series of tubes. The heat, as it thus passes backward and forward, is radiated by the tubes and heats the water, and produces steam in the boiler. The smoke escapes through the chamber s and pipe t.

The water in the boiler should cover the No. 1 series of tubes only, and then the heat radiated from the No. 2 series will superheat the steam generated by the No. 1 series.

A simple portable apparatus is thus provided, by means of which vegetables, or any kind of food for animals, may be economically steamed and cooked, in any suitable vessel, by simply connecting the flexible education-tube n with that vessel, or any number of vessels in succession.

By opening the door h of the chamber g the No. 1 and No. 2 series of tubes may be readily cleaned.

I am aware that furnaces and boilers have been combined to form feed-steamers, and that tubes have been used to conduct heat from the furnace, through the boiler, in reverse ways, to produce and superheat steam; but I claim that my manner of forming an independent portable furnace with two independent chambers, r and s, each chamber having independent rear openings, adapting the furnace to be connected with the front end of a boiler having two series of connected

tubes, Nos. 1 and 2, open at their front ends, is novel and advantageous.

I claim as my invention—

In the construction of a feed-steaming apparatus, the boiler A, having the series of tubes Nos. 1 and 2 and the clearing-chamber g, and the detachable furnace B, having cham-

bers r and s, all arranged and combined substantially as and for the purposes shown and described.

JOHN B. MOFFATT.
